UNITED STATES PATENT OFFICE.

HERBERT H. HEWITT, OF NEW YORK, N. Y.

SLIDING DOOR.

SPECIFICATION forming part of Letters Patent No. 325,245, dated September 1, 1885.

Application filed June 13, 1885. (No model.)

To all whom it may concern:

Be it known that I, HERBERT H. HEWITT, a citizen of the United States, residing at New York, county and State of New York, have 5 invented certain new and useful Improvements in Sliding Doors, of which the following is a specification.

This invention relates to sliding doors, and has for its object to improve the operation 10 of the same, and is particularly adapted to that class of car-doors constructed to move edgewise along the sides of the car away from the door-opening. Such car-doors have heretofore been provided at their four corners 15 with shoes or bearers adapted to slide on top and bottom door-tracks secured to the sides of the car. Great difficulty is sometimes experienced in manipulating car-doors of this class, as the shoes or bearers are caused to bind 20 on their tracks by reason of the buckling or warping of the doors, and also by the rubbing of the central part of the doors against the car-walls, due to the outward bulging of the car-walls. Now, my invention is designed to ob- 25 viate all difficulties arising from the buckling or warping of car-doors and bulging of car-walls, to simplify and lessen the cost of car-door fittings, and to provide a secure locking device for the doors. In the first place I so 30 make the connections or fittings of the car-door as to embrace the principle that three points of support or bearings triangularly ar- 35 ranged always provide a steady base or free- working bearings, irrespective of the form of the structure to which they are applied; and in applying this principle of construction to car-doors one of the supports or bearings may be placed at the upper part of the front or leading edge of the door, a second at the lower 40 end of the front or leading edge, and the third one at or on the rear or following edge of the door, and preferably at or near the central part of the same; and in conjunction with these three supporting shoes or bearers are used 45 three separate rails or tracks, each having a length about equal to the distance the car- door is moved, thus saving over the old style one shoe or bearer and one - quarter of the track or rail, as with ordinary sliding doors 50 four shoes or bearers are used and two tracks or rails, each equal in length to twice the dis-

tance the door is moved. A further saving in cost of fittings is had in that the operating-handle, which is a separate fitting in ordinary doors, is made a part of or integral with the 55 shoe or bearer attached to the rear or following edge of the door, and which slides on the rail attached to the central part of the car- body, said shoe and rail also being so made as to constitute a locking device for the door. 60

My invention also embodies, in the operation of sliding doors, the principle long applied to sliding windows and shades of carriages and cars and to sliding doors, as shown in the United States Patent No. 197,813, bearing date December 4, 1877, by which a window, shade, or door is caused to slide in guides or ways to and from its opening in direction longitudinal thereto, and its front or leading edge is caused to move obliquely into the opening when it is about closed, and the rear or following edge is moved laterally into its side of the opening when the window, shade, or door is directly opposite the same, thus bringing the window, shade, or door within the framework or door-posts; but to describe my invention more particularly I will now refer to the accompanying drawings, in which—

Figure 1, Sheet 1, is a view showing part of the side of a car and my improved sliding-door attachments. Fig. 2, Sheet 1, is a horizontal sectional view on the line *x x*, showing the door closed. Fig. 3, Sheet 1, is a similar view showing the door open. Fig. 4, Sheet 1, is a vertical section on the line *y y*, showing the 85 door open. Fig. 5, Sheet 2, is an enlarged view of a part of the central guide-rail and its bearing-shoe in section, showing the rear edge of the door in closed position. Fig. 6, Sheet 2, is a similar view showing the rear edge of 90 the door moved out of the door-opening. Figs. 7 and 8, Sheet 2, are edge and back elevations, respectively, of the central bearing-shoe; and Fig. 9, Sheet 2, is a view representing my improved method of operating car-doors applied 95 to a hanging door.

In the application of my invention no change is made in the construction of the car-body. The top and bottom door-tracks, 65 and 66, are secured to the side of the car above and below 100 the door-opening, but do not extend beyond the door-opening, and instead of being paral-

parallel or partly parallel to the side of the car they are arranged at an angle thereto, their rear ends being at a sufficient distance from the side of the car to permit the door to slide freely 5 from the opening along the car parallel thereto. The door is provided with a shoe, 70, at its front end, which embraces and slides on the bottom door-track, 66, and a shoe or hanger, 68, which embraces the top door-track, 65.

10 To support and control the movement of the rear end of the door, a rail or track, *a*, is secured about midway between the tracks 65 and 66 to the side of the car, and a shoe or bearer, *b*, constructed to embrace the rail *a*, is secured to the rear end of the door. This rail

a extends from the door along the side of the car to a distance about equal to the width of the door, and its end is bent at right angles and securely fastened to the inside of the door-post 44, the bent part *a'* being reduced in width, as shown at Fig. 4 and in the enlarged views, and its outer end, *a''*, is bent inwardly, for the purpose hereinafter explained. The shoe or bearer *b* is secured by screws or rivets to the outside of the door, near its edge, and is provided with an inwardly-projecting block, *b'*, having horizontal flanges *c c'*, so spaced as to embrace the rail *a*, the upper flange, *c*, taking the weight of the rear end of the door by resting on the top of the central rail, *a*, and vertical flanges *d d'*, projecting from the edges of the flanges *c c'*, arranged to bear against the inner side of the rail *a*, to hold the shoe *b* always thereon, and so spaced as to pass over the narrowed bent end *a'* of the rail *a*. The block *b'* is recessed, as clearly shown in Figs. 5 and 6, to admit the corner of the rail *a*, when the rear edge of the door is moved into the door-opening, as at Fig. 6.

40 In line with the flanges *c c'* are the perforated lugs *e* and *e'*, projecting from the edge of the shoe *b* above and below the rail *a*, adapted to receive the door pin or staple 74, to lock the door when closed. On the front of the shoe *b* is the handle 78, and for convenience and cheapness of manufacture and application the shoe *b'*, handle 78, guiding and controlling flanges *c c' d d'*, and locking-lugs *e e'* are of one piece of metal, preferably a malleable-iron casting. The door, when closed, sets within the door-posts 44, or in rabbets or recesses formed therein, said rabbets or recesses being shown in the drawings as produced by the sheathing 52, which is secured to the front of the door-posts, but does not entirely cover the same. To open the door, the rear end is moved outward until it is clear of the door-post 44 or sheathing 52, the flanges *d d'* of the shoe *b*, by coming in contact with the inside face of the rail *a*, preventing any further movement in this direction. The door is then moved along its supporting-tracks, the central track, *a*, passing through an opening in the rear stile and between two central rails of the door; and 55 the bent end *a''* of the central track forms a stop for the door, when it is fully opened parallel to the side of the car, by the flanges *d d'*

of the shoe *b* coming in contact therewith. In closing the door the front end, being guided by the inclined tracks 65 66, moves obliquely into the door-opening against the front door-post, and the rear end is pushed into the opening within the edge of the sheathing 52, the corner of the rail *a* entering the recess in the block *b'* of the shoe. The lugs *e e'* are then so located that the door pin or staple 74, which is connected to the shoe by means of a chain, can be passed through them and behind the rail or track *a*, thus preventing the outward movement and opening of the door. The lower end of the pin or staple 74 is perforated for the reception of a seal or other suitable securing device.

10 In applying my improvements to hanging doors the plan illustrated in Fig. 9 may be adopted, the upper front end being provided with a shoe or hanger, 68, which supports this end of the door on the top door-track, 65, the bottom door-track, 66, being secured to the bottom of the door, which is guided and controlled by the bracket-shoes 70, secured to the car, the central track or rail, *a*, and shoe *b* being as before described.

15 From the preceding description of my improved three bearing-supports applied to car-doors the application of the invention to other forms of sliding doors will be readily suggested.

20 What I claim, and desire to secure by Letters Patent, is—

1. In combination with a sliding door, three short bearers or supports attached thereto, one at the upper and one at the lower part of the front edge, and the other at or near the central part of the rear edge, and three independent fixed tracks or guides, one secured above the door-opening, one below the door-opening, and the other one extending from the central part of one side of the door-opening, thus providing the door with three bearing-points 105 triangularly arranged for all positions occupied by the door, substantially as set forth.

2. A car-door provided with three bearers or supports attached thereto, one at the upper part and one at the lower part of the front edge, and the other one at or near the central part of the rear edge, in combination with three independent tracks or guides secured to the car-body, one above and one below the door-opening, arranged at an angle to the side of the car, and the other one extending 115 from one side of said opening and secured in a central position to one side of the car-body, parallel thereto, substantially as and for the purpose set forth.

3. The combination, with a central guide-track secured to the car-body, of a bearer or shoe adapted to slide thereon, secured to the rear edge of the door, and an operating-handle forming a part of or integral with said bearer or shoe, and means, substantially as described, for supporting and guiding the front end of the door, substantially as set forth.

4. The combination, with a central rail attached to the side of the car-body, and with

- its end narrowed and bent at right angles and secured to the door-post, of a sliding shoe or support attached to the door, and having a bearing-surface which embraces the longitudinal part of the rail, and projecting flanges which bear against the inside of the same and arranged to pass over the bent end of the rail, substantially as and for the purpose set forth. 5
- 10 5. A guide rail or track secured to the central part of the wall of a car-body, with its end bent at right angles and secured to the door-post, and a bearer or support secured to the car-door, constructed to bear on the rail or track, and provided with a locking device adapted to engage with the rail or track when the bearer or support passes over the bent end of the rail or track, in combination, substantially as set forth. 15
- 15 6. In a sliding car-door, in combination, the top door-track, 65, the shoe or hanger 68, the bottom door-track, 66, the shoe 70, the central rail or track, *a*, the supporting-shoe *b*, and the car-door and car-body, substantially as and for the purpose set forth. 20
- 25
7. In combination, the central rail or track, *a*, the supporting-shoe *b*, with the handle 78, forming a part thereof, or integral therewith, and the car-door and car-body, substantially as and for the purpose set forth. 30
8. The shoe *b*, provided with recessed block *b'*, bearing-flanges *c c'*, and stop-flanges *d d'*, in combination with the rail or track *a*, with narrowed bent end *a'*, and the car-door and car-body, substantially as and for the purpose set forth. 35
9. In combination, the shoe *b*, bearing flanges *c c'*, stop-flanges *d d'*, the perforated projecting lugs *e e*, the door pin or staple 74, the central rail, *a*, and the car-door and car-body, 40 substantially as and for the purpose set forth.

In testimony whereof I have hereunto set my hand, at New York, county and State of New York, this 17th day of March, 1885.

HERBERT H. HEWITT.
